[57] CLAIM

The ornamental design for a mouthpiece for game calls, as shown and described.

DESCRIPTION

FIG. 1 is a top perspective view of a mouthpiece for game calls showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of a second embodiment thereof, wherein the only difference resides in the call opening portion; and,

FIG. 9 is a perspective view of a third embodiment thereof, wherein the only difference resides in the call opening portion.
